APPARATUS FOR BRAKING SHUTTLES IN
LOOMS FOR WEAVING

Rudolf Rossmann, Gauting, near Munich, Germany, assignor to firm Tefag Textil-Finanz A.-G., Zurich, Switzerland

Application June 1, 1933, Serial No. 673,810
In Germany June 4, 1932

7 Claims. (Cl. 139—185)

This invention relates to apparatus for braking shuttles in looms for weaving.

- For the purpose of braking a shuttle as this enters the shuttle box, it has been proposed to 5 provide the shuttle box with a swell consisting, for example, of a spring blade which projects into the shuttle box and frictionally engages the side of the shuttle, a buffer of hide or wood being usually provided against which the shuttle strikes.
- 10 With arrangements of this type the swell tends to apply a sudden braking force to the shuttle as soon as this enters the box, whilst, furthermore, the shuttle is not always sufficiently braked with the result that it strikes the buffer with such force 15 as to produce undesirable vibrations which are transmitted to the loom as a whole. When several swells have been provided so as to act successively on the shuttle during its movement into the box, a smooth progressive braking of the shuttle has not been obtained, chiefly because the 20 swells have not been capable of acting independently of each other, and the present invention has for its object to overcome these difficulties.

- According to the invention there is arranged in 25 the shuttle box at least one braking element which can be displaced by and act on the shuttle when this enters the box, the braking force thus applied to the shuttle increasing progressively during displacement of the braking element.
- 30 As opposed to known shuttle braking devices therefore in which the braking force is suddenly applied to the shuttle and remains substantially constant, braking apparatus embodying the present invention applies a braking force which increases gradually or step-by-step as the shuttle passes into the shuttle box. In this way substantially the whole of the energy of the moving shuttle is dissipated by the braking apparatus and the shuttle can always be brought to rest in 35 approximately the same position in the box even when variations in the shuttle speed occur.

- Preferably two or more braking elements or 40 swells are arranged to project into the shuttle box so as to be successively displaced and to act 45 on the shuttle as this passes into the box, each braking element being yieldingly pressed towards the shuttle independently of the other braking elements. The braking elements are thus successively engaged and displaced by the shuttle so that the braking effect thereon progressively increases. If desired the force necessary to displace a braking element is the greater the more remote the element is from the open end of the shuttle box, the tension or 50 loading of the braking elements being adjustable 55

individually or collectively. A curve representing the braking force applied is thus asymptotic. Preferably means are provided for moving all the braking elements out of engagement with the shuttle after this has come to rest in the shuttle 5 box, each braking element being conveniently loaded pneumatically, hydraulically or by a spring or weight.

The last braking element to be engaged by the shuttle as this passes into the shuttle box may 10 be associated with an indicating device or means for stopping the loom. In this way, when the shuttle does not fully pass into the shuttle box the braking element which is normally the last to be engaged and displaced by the shuttle is 15 not actuated and the said device or the means for stopping the loom is rendered operative.

Each braking element may be in the form of a spring plate the free end of which is inclined towards the inner end of the shuttle, the spring 20 plates being preferably carried on a common supporting member which can be adjusted in relation to the path of the shuttle.

Instead of employing a series of braking elements as above described apparatus according to 25 the invention may comprise a plunger arranged in a cylinder forming part of the shuttle box so that the plunger lies in the path of the shuttle, a series of ports being provided in the wall of the cylinder which ports are closed successively by the plunger as this is displaced into the cylinder by the entering shuttle.

Six constructions according to the invention are illustrated somewhat diagrammatically and by way of example in the accompanying drawings, in which

Figure 1 gives three curves indicating the braking force applied to a shuttle by known means and by means according to the invention,

Figures 2 and 3 are two further curves which 40 indicate respectively the speed of the shuttle with a known form of braking and with braking according to the invention,

Figures 4 and 5 illustrate in sectional side elevation one construction according to the invention,

Figures 6 and 7 illustrate another construction, and

Figures 8, 9, 10, and 11 show respectively four further constructions each embodying the invention.

In Figure 1 the curves are plotted with distance of travel of the shuttle as abscissae X and braking forces Y as ordinates. With known forms of shuttle swell the braking force during 55

the passage of the shuttle into the shuttle box is indicated by the curve A from which it will be seen that substantially the full braking force is applied from the moment when the shuttle 5 commences to enter the shuttle box, this force remaining constant until the shuttle comes to rest. The curve B indicates the braking force applied to the shuttle by one form of apparatus according to the invention, whilst the curve C indicates the braking force applied by another form of braking apparatus also according to the invention. From curve B it will be seen that the braking force applied gradually rises from zero value at the moment when the shuttle commences 10 to enter the shuttle box, whilst the curve C indicates a braking force which increases asymptotically.

The curve illustrated in Figure 2 represents the speed of the shuttle during its passage from 20 one shuttle box, through the shed, until it comes to rest in the other shuttle box. The left hand end of the curve in Figure 2 shows the sudden rise in speed of the shuttle as motion is imparted to it by the picker, the speed of the shuttle 25 falling slightly as the shuttle passes through the shed. When the shuttle enters the shuttle box after passing through the shed, the braking force applied to it remains substantially constant so that its speed decreases as indicated by the 30 straight line at the right hand end of Figure 2. In Figure 3 the speed curve illustrates the speed of the shuttle when braking means according to the invention are employed, and it will be seen that when the shuttle enters the shuttle box 35 after passing through the shed, the braking force gradually increases so that the decrease in speed of the shuttle is not represented by a straight line as in Figure 2 but by a curved line which indicates that the speed of the shuttle is reduced progressively. The curved part of the speed curve at the right hand end of Figure 3 is asymptotic, that is to say approaches an ordinate to the right of this curved portion in such a manner that it will not meet such ordinate within 40 a finite distance.

It will therefore be seen that even if fluctuations take place in the speed of the shuttle, since braking of the shuttle is effected progressively variations in the curve which indicate the reduction in speed of the shuttle during braking will be less than the variations which will take place in the corresponding curve when known forms of braking are applied and which would have a speed curve inclined to the abscissae, for example 55 as shown towards the right hand end of the curve in Figure 2.

Figures 4 and 5 illustrate one construction of braking apparatus according to the invention. In this construction the shuttle 1, after passing 60 through the shed, enters the shuttle box 2 and successively engages braking elements 3a, 3b, 3c, 3d, 3e, and 3f. Each braking element is bevelled off, as shown, on that side adjacent to the open end of the shuttle box so that wear on the shuttle 65 is reduced. The braking elements 3a, 3b, 3c, 3d, 3e, and 3f are loaded respectively by springs 4a, 4b, 4c, 4d, 4e, and 4f which are adjustable by means of screws 5a, 5b, 5c, 5d, 5e, and 5f threaded to engage a part of the wall of the shuttle box 2. 70 The braking element 3f is furnished with an L-shaped extension 6 guided in a bore in the shuttle box 2 and arranged to pass between two fixed contacts 7 respectively connected to two terminals of an electric circuit 8.

75 When therefore the shuttle 1 has passed through

the shed, it enters the shuttle box as shown in Figure 4 and successively forces the braking elements 3a, 3b, 3c, 3d, 3e, and 3f outwards against the action of their loading springs 4a, 4b, 4c, 4d, 4e, and 4f, whereby the braking force is progressively applied to the shuttle. When the shuttle arrives at the end of its inward movement and thereby forces the braking element 3f outwards, the contacts 7 are opened as shown in Figure 5, the circuit 8 being at this moment closed at another point by means not shown. If however the shuttle 1 does not properly enter the shuttle box 2 and thus does not move the braking element 3f to open the contacts 7, the closing of the circuit 8 will result in the loom being stopped. 10 Thus, the arrangement is such that when normal operation of the shuttle is taking place, the circuit 8 is always broken at at least one point, but when the shuttle fails to pass fully into the shuttle box 2, the circuit will be closed and the loom stopped, or a signal actuated so as to indicate 15 that operation of the loom should cease.

The desired progressive action of the braking elements 3a, 3b, 3c, 3d, 3e, and 3f may be obtained by adjusting the screws 5a, 5b, 5c, 5d, 5e, and 5f, or, if desired, this progressive action may be obtained by increasing successively the tension of the springs 4a, 4b, 4c, 4d, 4e, and 4f.

In Figures 6 and 7 an arrangement is shown suitable for use in braking shuttles of the gripping or nipper type. In this construction each braking element 3 is furnished with a lateral recess 9 arranged to cooperate with a projection 10 on a member 11, the projection 10 being somewhat smaller than the recess 9 so as to allow relative movement between each braking element 3 and the projection 10. As the nipper shuttle 1 enters the shuttle box, it successively forces the braking elements 3 outwards against the action of their springs 4, a projecting end of the member 11 serving to support the shuttle 1 from below, as shown in Figure 6. It is now necessary to release the shuttle in order to permit of its return to the projecting box, and to this end the member 11, which may be spring-controlled, is 45 moved so that it first releases the shuttle 1, as shown in Figure 7, whereupon the projection 10 engages all the braking elements 3 and moves them outwards against their springs 4. The shuttle then drops down from the position shown in 50 Figure 7 into engagement with means (not shown) whereby the shuttle is returned, for example outside the shed, to the projecting box.

A further construction for use with nipper shuttles is illustrated in Figure 8, in which the 55 braking elements are carried on a spindle 12 on the shuttle box 2 which is furnished with a brake-release device 13. Each braking element comprises a shoe 14 pivoted on the spindle 12 and carrying a leaf spring 4 the free end of which 60 bears against a set screw 5 threaded to engage the shuttle box 2. When the shuttle 1 enters the shuttle box after passing through the shed, it successively engages the shoes 14 and, turning these about the spindle 12, flexes the springs 4. 65 The release device 13 is now moved upwards as indicated by the arrow, thereby turning all the shoes 14 about the spindle 12 in the counter-clockwise direction so that the shuttle 1 is released and drops down into engagement with 70 means (not shown) for returning the shuttle to the projecting box.

In the construction illustrated in Figure 9, each braking element comprises a lever 14 pivoted on the spindle 12 and acted upon by a weight 75

15, the release mechanism being indicated at 16. The effective braking force applied by each braking element 14 to the shuttle 1 may be adjusted by engaging the weight 15 with one of several 5 notches 17 formed in the lever 14. Thus, when the nipper shuttle 1, after passing through the shed, enters the shuttle box 2, the levers 14 are successively engaged and turned about the spindle 12 in the counterclockwise direction against 10 the action of the weights 15. The release lever 16 is then rotated in the clockwise direction so that its inner end bears against all the levers 14 and turns these in the counterclockwise direction about the spindle 12. The shuttle 1 is in this way 15 released and drops down into engagement with means for returning the shuttle to the projecting box.

In the construction illustrated in Figure 10, the 20 braking elements 4 are in the form of spring blades having their free ends inclined towards the inner end of the shuttle box. The blades 4, which may be made of different tension and need not be parallel to each other, are carried in slots 18 formed in a member 19 which can be moved to 25 or from the shuttle 1 by toggle mechanism comprising levers 20a, 21a, 22a and 20b, 21b, 22b, which can be operated by means of a control rod 23. When the shuttle box 2 is to receive the shuttle 1 after this has passed through the shed, 30 the control rod 23 is driven inwards so that the member 19 and springs 4 it carries are moved inwards towards the path of the shuttle the toggle levers locking the member 19 in this position. The shuttle, as it passes into the shuttle box, is 35 progressively engaged by the springs 4 and is thus braked. Any tendency for the shuttle to rebound from the box is prevented due to the oblique arrangement of the springs 4 which will grip the shuttle 1 against reverse movement. If now the 40 shuttle is to be projected from the box 2, the control rod 23 is drawn outwards, thereby moving the member 19 away from the shuttle 1 so that this is free to move out of the shuttle box either in the direction of the length of the weft or 45 in a direction transversely thereto.

Figure 11 illustrates a further construction in which, instead of employing a series of spring or weight loaded braking elements, a single pneumatically loaded braking element is employed. 50 To this end the shuttle 1, on entering the shuttle box 2, engages a plunger 24 so that this is moved inwards within a cylinder 25. When the plunger 24 commences to move inwards air within the chamber 25 can escape through a series of bores 55 26a, 26b, 26c, 26d, 26e, and 26f, the plunger covering these bores successively so as progressively to reduce the rate at which air can be displaced from the cylinder during the inward movement of the plunger. In this way the braking effect on 60 the shuttle 1 will increase progressively as the shuttle passes into the shuttle box. The shuttle can then be projected from the shuttle box 2 by means of a spring 27 which is compressed during the inward movement of the plunger 24, air being 65 admitted to the chamber 25 during the projecting movement of the plunger 24 through a plate valve 28 controlled by a spring 29 which normally holds the plate valve over an air inlet aperture 30.

It will be understood that instead of loading 70 the braking elements by means of springs as above described these may be loaded pneumatically or hydraulically and, though an indicating device or loom stopping mechanism has only been included in the construction described with reference to Figures 4 and 5 such indicating device

or loom stopping mechanism may be similarly employed in conjunction with other constructions such, for example as those described above with reference to Figures 6 to 10 inclusive.

I claim:—

1. In an apparatus for braking shuttles in looms for weaving, the combination with a shuttle box of a plurality of individual braking elements which project into the shuttle box and are adapted to be successively displaced by and 10 to successively and individually act on the shuttle as this passes into the box, individual resilient means connected with each individual braking element, said means operating and pressing the element with which it is connected onto the 15 shuttle independently from all the others of said elements, whereby stepwise braking action only is applied to the shuttle, said braking elements comprising longitudinal blocks which are adapted to 20 slidingly reciprocatingly move in a direction which is perpendicular to the direction of movement of the shuttle, substantially as described.

2. In an apparatus for braking shuttles in looms for weaving, a shuttle box; a plurality of individual reciprocatingly and bodily movable braking elements which are supported separately and independently from one another, project into the shuttle box, and are adapted to be successively displaced by, and to successively and entirely independently from one another, act on the shuttle as this passes into the box; and individual resilient means connected with each individual braking element, said means operating and pressing the element with which it is connected onto the shuttle independently from all 25 the others of said elements, whereby stepwise braking action only is applied to the shuttle.

3. In an apparatus for braking shuttles in looms for weaving, the combination with a shuttle box of a plurality of individual braking elements which all project from one side into the shuttle box and are adapted to be successively displaced by, and to successively and entirely independently from one another, act on one side 40 of the shuttle as this passes into the box; individual resilient means connected with each individual braking element, said means operating and pressing the element with which it is connected onto the shuttle independently from all 45 the others of said elements, whereby stepwise braking action only is applied to the shuttle; and individual adjusting means individually connected with said individual resilient means for individually and independently from one another 50 adjusting the braking force of the individual elements.

4. In an apparatus for braking shuttles in looms for weaving, the combination with a shuttle box, of a plurality of individual braking elements which all project from one side into the shuttle box and are adapted to be successively displaced by, and to successively and entirely independently from one another, act on only one side of the shuttle as this passes into the box; individual resilient means connected with each individual braking element, said means operating and pressing the element with which it is connected onto the shuttle independently from all 60 the others of said elements, whereby stepwise 65 braking action only is applied to the shuttle; and adjusting means connected with said resilient means for adjusting the braking force of said braking elements.

5. In an apparatus for braking shuttles in 70

75

looms for weaving, the combination with a shuttle box, of a plurality of individual braking elements which project into the shuttle box and are adapted to be successively displaced by, and to successively and entirely independently from one another, act on the shuttle as this passes into the box; individual resilient means connected with each individual braking element, said means operating and pressing the element with which it is connected onto the shuttle independently from all the others of said elements, whereby stepwise braking action only is applied to the shuttle; and individual adjusting means connected with each of said resilient means for individually adjusting the braking force of said braking elements, said adjusting means being accessible from without the shuttle box.

6. In an apparatus for braking shuttles in looms for weaving, the combination with a shuttle box, of a plurality of individual braking elements which project into the shuttle box and are adapted to be successively displaced by, and to successively act on, the shuttle as this passes into the box; individual resilient means connected with each individual braking element whereby each braking element is yieldingly pressed towards the shuttle independently from

the other braking elements; an extension connected with that one of said braking elements which is engaged last by the shuttle passing into the box, and an electric switch connected with said shuttle box and adapted to be operated by said extension upon engagement of the shuttle with said last engaged braking element.

7. In an apparatus for braking shuttles in looms for weaving, the combination with a shuttle box, of a plurality of individual braking elements which project into the shuttle box and are adapted to be successively displaced by, and to successively and individually act on, the shuttle as this passes into the box; and individual resilient means connected with each individual braking element, said means operating and pressing the element with which it is connected onto the shuttle independently from all the others of said elements, whereby stepwise braking action only is applied to the shuttle, said braking elements comprising longitudinal blocks having a rectangular configuration and being adapted to slidably reciprocatingly move in a direction which is perpendicular to the direction of movement of the shuttle.

RUDOLF ROSSMANN.
